CLIFFORD BRODERICK CRONAN, OF SHELBOURNE FALLS, MASSACHUSETTS.

FLYING-MACHINE.

965,622.

Specification of Letters Patent. Patented July 26, 1910.

Application filed February 17, 1909. Serial No. 478,409.

To all whom it may concern:

Be it known that I, CLIFFORD BRODERICK CRONAN, a citizen of the United States, and a resident of Shelburne Falls, in the county 5 of Franklin and State of Massachusetts, have invented a new and Improved Flying-Machine, of which the following is a full, clear, and exact description.

This invention relates to a class of flying 10 machines which are capable of ascending in and being navigated through the air, without the employment of gas lighter than air to effect the levitation of the apparatus.

The purpose of my invention is to provide 15 novel details of construction for an air ship, that enable the vertical ascent thereof by contained mechanism, effect its progressive movement laterally in any direction and at any speed within the capacity 20 of said mechanism; further, that will permit the ship to be raised vertically to any height desired, be held stationary while at a desired point, and be controlled in its descent so that jar or shock from contact with 25 the earth is neutralized.

The invention consists in the novel construction and combination of parts, as is hereinafter described and defined in the appended claims.

30 Reference is to be had to the accompanying drawings forming a part of this specification, in which similar characters of reference indicate corresponding parts in all the views.

35 Figure 1 is a side view of the improved air ship, parts being broken away and other details indicated by dotted lines; Fig. 2 is a reversed plan view of the same; Fig. 3 is an enlarged longitudinal partly sectional side view of rudder mechanism, taken substantially on the line 3—3 in Fig. 2; Fig. 4 is an enlarged transverse sectional view, substantially on the line 4—4 in Fig. 2; Fig. 5 is an enlarged partly sectional plan view of 40 details of the rudder mechanism, seen in the direction of the arrow 5 in Fig. 3; Fig. 6 is an enlarged transverse sectional view of the forward portion of the ship, substantially on the line 6—6 in Fig. 1; Fig. 7 is a partly sectional side view, substantially on the line 7—7 in Fig. 2 seen in the direction of the arrows therat; Fig. 8 is a longitudinal partly sectional view, of the front portion of the machine; Fig. 9 is an enlarged 45 longitudinal sectional view of novel details taken substantially on the line 9—9 in Fig.

10; and Fig. 10 is an enlarged transverse sectional view of parts shown in Fig. 9, taken substantially on the line 10—10 in Figs. 1 and 9.

In the drawings, 12 indicates the base portion of a main frame for the machine, consisting of the following details: A pair of parallel spaced runners 12^a form sills for the frame and 12^b cap members that are 60 joined with the runners by a plurality of inclined braces, said runners curving upward toward the front end of the frame. On the cap members 12^b a plurality of spaced transverse frame members 13 are secured that 65 project at each side of the frame an equal distance, as shown at 13^a in Fig. 6.

A suitable number of posts 14 are erected vertically from each frame member 12^b, and said vertically-disposed frame members are 70 joined together at their upper ends by horizontal frame members 14^a that are equal in length and parallel with the cap members 12^b.

On the frame members 14^a, transverse 80 spacing members 14^b are secured, which extend outside of the longitudinal frame members 14^a an equal distance, as shown in Fig. 6 at 14^c, and on the outer ends of the extensions 14^c inclined frame members 15 are 85 seated at their lower ends, and at their upper ends are in pairs oppositely secured upon a longitudinally-disposed ridge-beam 16.

Two wing-like aeroplanes 17 are provided, having similar dimensions, these having an equal length with the longitudinal frame members 12^b, whereon they are hinged at corresponding side edges, as indicated at 90 a in Figs. 1 and 6. A suitable motor 18 is 95 supported on a transverse floor b, that is seated and secured on certain of the transverse frame members 13; preferably said motor is of a type having a rotary piston rod c that extends from each end of the motor cylinder through gear casings d, and at the front end has a bevel gear e secured thereon.

A plurality of propeller screws 19 are employed, preferably of equal dimensions and 100 having their blades 19^a in the form of continuous spirals, of a diameter and pitch between their turns that will adapt them to exert powerful lifting force when rapidly rotated in a proper direction. The pair of 110 lifting screws 19 are each journaled at each end of the central shaft from which the spi-

ral blade radiates, in suitable boxes that are placed centrally on one of the transverse frame members 14^b and the ridge beam 16 a proper distance apart, so that said screws 5 will be respectively positioned a distance beyond a corresponding end of the motor 18. The lower end of the center shaft of each lifting screw 19 extends a short distance below the rotatable support therefor, and on 10 said ends similar bevel gears *g* are mounted and secured.

Supported from the frame members 14^b are hanger boxes *g'* which carry a driven shaft *g²*, on the ends of which are secured 15 two bevel gears *g³* that are respectively meshed with the gears *g*.

Upon two bracket arms *h* and *d'*, that are respectively mounted upon a transverse frame member carried by the frame members 20 14^b and on the forward gear casing *d*, a vertical driving shaft 20 is journaled, as shown in Figs. 1 and 7, a bevel gear *e'* that is secured on the lower end of said shaft meshing with the bevel gear *e*.

25 On the upper end of the driving shaft 20, a bevel gear *h'* is secured, that meshes with a bevel gear *h²* carried by the driven shaft *g²*, thus establishing a geared connection between the piston rod *c* and the lifting screw 30 shafts 19.

A propeller wheel 21, having a plurality of radial blades thereon, of sufficient area to adapt said propeller for effective service in the propulsion of the air ship, is mounted 35 upon one end of a horizontal shaft *i*, that is rotatably supported on the rear portion of the main frame. A tumbling shaft *i'* is connected at the forward end thereof with the rear end of the piston rod *c*, by a universal coupling *i²*; and by means of a similar coupling *i³*, said shaft is coupled with the forward end of the horizontal shaft *i*.

It will be noted that the geared connection 40 between the forward end of the piston rod *c* and the connection of the tumbling shaft *i'*, at its ends with the rear end of the piston rod and shaft *i*, transmits rotary motion from the motor to the lifting screws 19, 19^a, and the propeller screw 21. It will 45 also be seen that the rotation of the propeller screw 21 in a proper direction will cause a progressive movement of the air ship while the lifting screws 19, 19^a cause its elevation.

50 It is contemplated to provide means for changing the speed of rotation to be given to the shaft 20 and the shaft *i'*, and as such change gears which are to be placed in the casings *d*, *d'*, are in common use, it is not 55 considered necessary to illustrate the same in the drawings.

In further consideration of the aeroplanes 60 17, it will be seen that these are each formed with a light but strong frame, oblong and 65 nearly rectangular, having transverse braces

disposed at intervals, their outer corners being rounded as shown in Fig. 2, and as before mentioned, each frame for a respective aeroplane is hinged at proper points *a* on an adjacent longitudinal member 12^b of 70 the main frame. Preferably the aeroplane frames are rendered concavo-convex transversely considered, their concave sides being lowermost, and said frames may be covered with any suitable fibrous fabric, or if preferred, thin sheets of aluminum may be substituted for cloth. The positions given to the aeroplanes 17 adapts them for contact with the lateral extensions 13^a of the transverse frame members 13, and they are normally held thus disposed in nearly horizontal planes by means of contractile springs 75 17^a, which are attached by one end of each upon the frame members 13^a and at their upper ends are connected to the 80 ends of wire ropes 17^b, that are extended up to and over pulleys 17^c, pendent from the lateral extensions of the horizontal main frame members 14^b. From the pulleys 17^c, the flexible connections 17^b trend downward 85 and outward into engagement with loose pulleys 17^d, and at their lower ends are secured upon the outer side edges of the aeroplanes 17, as represented in Fig. 6, this connection of parts serving to dispose the wings 90 or aeroplanes as shown in said view.

Near the front end of the main frame 12, a seat 12^e is located for the accommodation of the operator who controls the flight of the ship, and conveniently near to said seat 100 a foot rest is afforded by the provision of a basket 12^d or the like, which is pendent from members of the main frame. Upon a transverse bar 12^e fixed on the runners 12^a, two arms 12^g are pivoted at their lower ends, and are so relatively positioned that the operator seated on the seat 12^e may engage 105 his feet with pedals 12^h that are attached to the upper ends of said arms.

Adjacent to the arms 12^g, loose pulleys *k* 110 are supported on bracket frames that project from the main frame, these loose pulleys affording support for two flexible connections 12^f that at one end of each are attached upon a respective arm 12^g and thence trend rearwardly in engagement with other loose pulleys *k'*, their rear ends being attached to the under sides of respective aeroplanes 17, as is best shown in Fig. 6.

115 It will be apparent, that by an engagement of his feet with the pedals 12^h, an operator while occupying the seat 12^e may depress either or both aeroplanes 17 more or less as occasion may require, this depression being indicated by dotted lines for one aeroplane at the left in Fig. 6.

120 As shown in Figs. 1, 2 and 8, a plurality of ground wheels 12^m are rotatably supported on the main frame 12, and normally 125

project a short distance below the runners 12^a, said wheels affording means for the convenient transporting of the entire apparatus on the ground as may be desired.

5 They also cushion the impact of the ship when it is lowered and prevent objectionable shock when the apparatus is seated on the earth.

The bottom, sides and top of the main 10 frame are covered with strong fibrous fabric 22, that is supported upon light strong ribs 23, the latter being bent into arched form, as is indicated in Fig. 6, and preferably the cover 22 is extended in its upper portion at 15 each end so as to overhang the lower portion, thus providing a hood at each end of the cover, this construction appearing in Fig. 1.

A novel detail for the control of the improved air ship consists of a steering device 20 that embodies the following details: From the main frame 12, a horizontal supplementary frame extends rearward, consisting of two frame bars 23 that are secured on the longitudinal main frame members 12^b, these 25 frame bars being preferably curved outward near their rear ends that are spaced apart by a flat transverse frame bar 23^a. The frame bars 23 are reinforced by a transverse brace 23^c, that is attached thereto at its 30 ends a suitable distance from the transverse frame bar 23^a, as is shown in Fig. 2. Upon the transverse frame bar 23^a, a gimbal ring is mounted consisting of an arched top portion 24, having parallel depending side 35 members 24^a formed thereon, which are integrally connected at their lower ends by a flat transverse bar 24^b, that is centrally pivoted upon the transverse frame bar 23^a, as indicated at *m* in Figs. 2, 3 and 4.

40 From the ridge beam 16, a brace bar 16^a is downwardly and rearwardly extended, said brace being lapped upon and pivoted to the arched portion 24 of the gimbal ring at its center, as shown at *m'* in Figs. 3 and 4.

45 The body of the rudder consists of a proper number of hoops *n*, formed of suitable rigid material, said hoops being shaped similarly to the form of the gimbal ring hereinbefore described, but of considerably 50 smaller diameter, and upon the hoops is stretched suitable fabric *n'*. As shown in Figs. 1 and 3, the ends of the rudder are sloped from the top downwardly and toward the center thereof, thus providing a hood-like overhang at each end of the rudder, 55 similar to the cover for the main frame of the machine, this provision in both cases being designed to lessen frictional resistance when the craft is being elevated. Centrally and 60 vertically in the rudder body, a rock shaft *n*² is loosely secured by an engagement of the ends thereof within sockets *n*³ that are oppositely affixed in a hoop *n* that is located at or near the longitudinal center of the 65 rudder.

In the gimbal ring members 24^a, the ends of a cross bar 24^c are affixed at points equally distant from the top of the arched member 24 and the flat transverse lower member 24^b, thus disposing said cross bar parallel 70 with a member 24^b and at the vertical center of the gimbal ring, as shown in Fig. 4.

A shaft 25 is secured by its rear end upon the rock shaft *n*² at the center of the latter, and thence extends forwardly in the body 75 of the hollow rudder parallel with the upper and lower sides of the same. As shown in Fig. 3, the shaft 25 is reinforced by brace rods *o*, that are extended in the same vertical plane from the upper and lower ends 80 of the rock shaft *n*² into contact with upper and lower sides of the shaft 25, whereon said extended ends are secured. In Fig. 4, truss rods *o'* are shown, that are engaged at their ends on the end portions of the rock 85 shaft *n*² and spread apart at their centers of length by spacing blocks, said rods affording lateral support for the rock shaft.

It will be seen in Figs. 3 and 4, that the shaft 25 is seated upon the cylindrical cross 90 bar 24^c, which adapts the body of the hollow rudder to rock longitudinally upon the cross bar, and further, that the pivotal engagement of the gimbal ring with the frame cross bar 23^a and brace bar 16^a, together with the 95 pivotal supports for the vertical rock shaft *n*², permit the rudder body to receive vertical and lateral rocking movement by similar movements respectively of the shaft 25 and the gimbal ring member 24.

From the outer ends of the transverse frame bar 14^b, at the rear end of the main frame, guy wires or rods *p* are rearwardly extended and are secured to the brace bar 16^a 105 on opposite sides, near the point of its pivotal engagement with the gimbal ring member 24, this connection of the guy wires serving to laterally support the rear end of the brace bar 16^a.

The preferred means for control of the 110 movements of the rudder from the front of the machine by a person occupying the seat 12^c, embodies the following details: A shifting bar 26 is supported to receive longitudinal rocking movement by a series of spaced 115 link plates *r*, that are pivoted at their upper ends on the main frame member 12^b, and upon said shifting bar at their lower ends, and, as shown, the equal length of the link plates adapts them for supporting the shifting bar parallel with and a suitable distance 120 below the frame member 12^b. The forward end of the shifting bar 26 is pivoted upon the lower end of an upright lever 26^a, that is pivoted on a suitable support, such as a 125 sector *q*, on the main frame of the machine, the upper end thereof being located conveniently for manipulation by a person seated on the seat 12^c. The rear end of the shifting bar 26 extends a distance rearward of 130

the propeller having the blades 21, and upon said rear end is pivoted the lower end of an angle lever member 27, said member being rockably supported on the transverse brace 23^c. In order to render the longitudinal movement of the shifting bar 26 uniform, it is found advantageous to place a suitable weight thereon; and, as shown in Figs. 1 and 7, a water cooler 18^a for the engine 18 is hung on said bar, the weight of the cooler serving to depress the shifting bar 26 and adapt it for proper reciprocal movement. To facilitate the attachment of the cooler to the shifting bar, hose 18^b extend from the motor 18 to ends of the cooler for a proper circulation of water. Jointed to the upright member 27 is a horizontal member 27^a, which projects toward and has a loose engagement with the front end of the shaft 25, the preferred means for connecting said parts being clearly shown in Figs. 3 and 5. It will be seen, that the weight imposed on the shifting bar 26, causes it to assume a level position due to gravity and thus be adapted for enabling manual control of the rudder. The forward end of the shaft 25 is slotted, thus affording two spaced limbs *s* thereon, which latter are longitudinally and oppositely slotted intermediate their ends as shown in Figs. 3 and 5. The horizontal member 27^a of the angle lever is longitudinally perforated centrally from its end forwardly, and this perforation is threaded in its wall, wherein a coupling bolt 28 is screwed. The coupling bolt 28 is headed on one end and before its screwed insertion into the angle lever member 27^a is loosely inserted through a perforated slide block 29, that loosely occupies the space between the limbs *s*. Two studs *t*, *t*, are screwed at their threaded ends into opposite threaded perforations in the slide block 29 after passing loosely through the slots in the limbs *s*. It will be seen that the described connection of parts affords a loose slidable coupling between the member 27^a of the angle lever and the end of the shaft 25, which will prevent binding at the joint, and adapt a rocking movement of the angle lever that may be effected by a reciprocation of the shifting bar 26, to correspondingly rock the body of the rudder from a horizontal position.

Inspection of Fig. 3 will show that a forward slidable movement of the shifting bar 26 will push the lever member 27^a rearward and rock the rear end of the rudder upward, and, obviously, a reversed longitudinal movement of the shifting bar, that will push it rearward, will pull the angle lever member 27^a forward and depress the rear end of the rudder correspondingly.

To conveniently effect a lateral rocking movement of the rudder toward either side of the craft, one means is illustrated, consisting of the details shown in Figs. 1, 2, 6

and 8. Directly forward of the seat 12^c, a short upright shaft *u* is rotatably mounted upon the main frame 12, said shaft having a hand wheel *u'* secured on its upper end and upon the lower end a grooved pulley *u*² is affixed. A thin wire rope *u*³ is wrapped one or more turns around the periphery of the grooved pulley *u*² near its center of length and thence the two substantially equal portions or runs of the cable are extended rearward and attached at their ends oppositely upon the lower portions of the limbs or side members 24^a of the gimbal ring, as shown in Figs. 2 and 4, said runs being supported at intervals upon grooved pulleys *v* as shown in Fig. 2. Assuming that the operator occupies the seat 12^c, it will be apparent that by turning the hand wheel *u'* toward the right side of the main frame 12, the left hand run of the cable will be shortened, which will rock the rear end of the rudder leftward, and a reversed movement of the hand wheel or toward the left side of said frame, will turn the rear end of the rudder rightward, the degree of such turning movements being determined by the rotatable movement of the hand wheel. It will be seen that the vertical rocking adjustment of the rudder and its lateral adjustment which are under complete control by a person occupying the seat 12^c, enables a positive directive control of the air ship in any desired direction.

To further explain the advantages derived from the novel construction of the details and their coöperative association, it will be noted that the controlled action of the lifting screws 19, 19^a, enables the operator to rise vertically without requiring an initial forward impetus to effect such a result. The lifting screws, by regulation of their speed, permits the operator to rise or descend at will, and thus avoid adverse currents of air, so that a maximum speed may be attained with the expenditure of minimum power. The coöperative action of the multi-bladed propeller wheel 21 with the lifting screws, enables progressive movement to be effected at a desired elevation; further, if the rotation of the propeller wheel is arrested and the lifting screws driven at a speed that will merely counteract the force of gravity, the air ship may be maintained nearly stationary over a selected point on the earth's surface.

In ascending, the wing-like aeroplanes 17 are lowered by pressure on the pedals 12^b, thus reducing the area of exposed surface when the ship is ascending. After a desired height is attained, the aeroplanes 17 may be permitted to assume horizontal positions, as shown by full lines in Fig. 6, and add to the levitation of the ship by gliding contact with the air. The aeroplanes 17 also aid in turning short circles by the depression of

one while the other is left extended, thus simulating the soaring action of a large bird, and by their extension as wings, serve to balance the ship when struck by lateral 5 wind currents.

As the propeller wheel may have its blades 21 of sufficient area to give proper progressive movement to the ship, the employment of a single wheel is of positive advantage, as 10 being located at the transverse center of the main frame, it will not have an unbalancing effect if by accident it becomes inoperative, as would be the case if two wheels were employed and arranged side by side and one 15 became disabled.

The construction and combination of parts that have been described, embody an example of my invention in its primary form, wherein a single pair of lateral rockable wings or aeroplanes is disclosed. It is to be understood, however, that in a further development of the invention, it is found 20 advantageous to employ a second or third pair of wings or lateral, rockable planes, 25 adapted for separate or simultaneous service in connection with other details of the invention, as will now be described. Referring to Figs. 1, 9 and 10, that show the application of a second pair of adjustable 30 planes, it will be seen that the second pair of adjustable planes are preferably positioned in the space defined by two pairs of inclined frame members 15 that are located 35 between the lifting screws 19, 19^a. Parallel with the horizontal beams 14^a and at a suitable distance therefrom, four boxes 50 are secured upon the two pairs of inclined frame members 15, and in each pair of said boxes at a respective side of the main frame a 40 shaft is journaled at its ends, thus spacing said horizontal shafts 51, 52, apart parallel with each other.

On each of two hubs that are mounted and secured upon the shaft 51 near each journal end thereof, a suitable number of radial arms 53 are mounted and project therefrom. An aeroplane 54, preferably constructed in 45 the form of a light frame, concavo-convex in cross section and covered with strong, 50 light, fibrous fabric, is near its side edges secured upon the outer ends of the radial arms 53, as shown at 55.

Oppositely from the concavo-convex plane 54, arms are projected at preferably 55 equal distances apart, said arms 57, of equal length at their outer ends, carrying a toothed sector 56, and between the arms 53 and 57, braces 59 are introduced, thus stiffening the structure.

60 On the shaft 52, an equal number of radial arms 53^a with that of the arms 53, are secured on hubs affixed at the ends of said shaft and at their outer ends are affixed upon an aeroplane 54^a, similar in every respect to the plane 54. Oppositely from the

arms 53^a, arms 57^a project radially, and on their projected ends a sector 56^a, that is the duplicate of the sector 56, is secured and it will be noted that the sectors 56, 56^a are disposed respectively concentric with the shafts 70 51 and 52. The radial arms 53^a are reinforced by braces 59^a, similar to the arms 59, and render the light but strong supports for the aeroplanes and sectors, rigid and adapted to withstand strains imposed thereon in 75 every direction, cross braces 59^b between the pairs of sectors aiding to effect this result.

Mounted upon two transverse frame members 14^b, between each pair of sectors 56, 56^a, are two similar bracket frames 60, 61, having bearing boxes in which the journal ends of two similar parallel shafts 62, 63 are rotatably mounted. On each end of the shaft 62, a spur gear 64 is secured, that meshes with a similar gear 65 on a corresponding end of the shaft 63. The spur gears 64, 65, respectively mesh with the toothed sectors 56^a, 56, thus establishing geared connection between the two shafts 62, 63, and the sectors 56, 56^a. 80

It will be noted that if the shaft 62 and spur gear 64 thereon are turned in the direction of the curved arrow, shown thereat in Fig. 10, said gear will reversely turn the gear 65 and these gears will, through the 85 rocking movement of the sectors 56^a, 56, lower the aeroplanes 54, 54^a from a horizontal to parallel vertical planes. 90

As shown in Figs. 9 and 10, flexible wire braces 55^a, are extended from the outer side 100 edges of the aeroplanes 54, 54^a, downwardly and engage spring-rotated rollers or drums 55^b that are positioned on the end portions 13^a of the transverse frame members 13, these braces or guy wires having such a 105 length that they become taut when the aeroplanes 54, 54^a are together rocked upwardly into a substantially horizontal plane and are arrested from further upward movement by said guy wires. The drums 55^b wrap up the 110 guy wires when the aeroplanes are lowered, and thus prevent slackness and entanglement with other parts.

It is of advantage to control the adjustment of the upper aeroplanes 54, 54^a, from 115 the seat occupied by the one who controls the other operative details of the flying ship. To this end, a shaft 66 is rotatably supported on the main frame, and carries at its rear end a spur gear 67 which is meshed 120 with the spur gear 64. The shaft 66 extends forward, receiving support at its forward end from a bracket arm 68 mounted on the main frame, and on said end a bevel gear 69 is secured, that meshes with a similar gear 125 70 that is affixed upon the upper end of a vertically and rotatably supported shaft 71. A bracket arm 72, erected on the main frame of the machine, loosely supports the lower portion of the vertical shaft 71, and on the 130

latter at its end a bevel pinion 74 is secured, which has meshed engagement with a similar bevel pinion 75 that is attached upon one end of a short shaft that is journaled on the 5 bracket arm 72 and at its opposite end is provided with a crank handle 76.

It will be seen in Fig. 1 that the crank handle 76, is so relatively disposed that a person seated at 12°, will be enabled to 10 manipulate said crank handle and control the aeroplanes 54, 54^a, so as to rock them either for their elevation into a horizontal position, or lower them so that they are vertically disposed, as is shown for the plane 54^a by 15 dotted lines in Fig. 10.

It will be evident that the provision of the supplementary pair of aeroplanes which have been described, will afford additional area for the soaring movement of the flying 20 machine, and that said planes when extended, steady the apparatus and counteract any tendency of the lifting screws to give gyroscopic movement to the airship.

To safely descend after the ship has attained a desired height, the motor 18 is reduced in speed of rotation of the piston rod 25 *c*, so that the spiral radial blades 19^a do not have force enough to overcome the gravity of the ship and its load, which will permit a slow downward movement thereof. The propeller wheel by an impact of its blades 21 on the air, will give a slow forward movement to the craft, so that when the wheels 12^m that are mounted on the runners 12^a impinge upon the ground, they will cushion the impact, and upon stopping the motor the ship will become stationary and maintain an upright position.

In further consideration of the operative 40 mechanism for the lifting screws 19, 19^a, the change gears that are located in the gear casings *d*, may be manually controlled by slide rods *d*², that are respectively coupled with the gear train in each casing and extend 45 forwardly, having their extended ends loosely connected with the upright levers *d*³, that are pivoted on the sectors *d*⁴, that are supported vertically on the main frame 12 adjacent to the seat 12^c, for convenient manipulation 50 by an occupant of said seat. It is not desired to limit the number of pairs of aeroplanes to two pairs, as it is feasible to employ more if desired.

Immaterial changes in the construction of 55 the minor details may be employed within the scope of my invention, and I claim all such modified construction and arrangement of the parts as may be embraced by the claims.

60 Having thus described my invention, I claim as new and desire to secure by Letters Patent:

1. In an airship, a rectangular main frame, and a protecting structure within 65 said frame, embodying a series of arched

ribs, and a pliable cover on said ribs, the cover projecting its arched upper portion at each end thereof, forming overhanging hoods.

2. In an air ship, a main frame, a rearward extension on said main frame, a rudder comprising a skeleton frame arched in its upper portion, parallel on the sides and flat on the bottom, said skeleton frame having a thin, pliable covering, means for supporting the skeleton frame so that it may be rocked longitudinally and laterally, means for effecting the longitudinal rocking movement thereof, comprising a shifting bar 75 rockably hung on the main frame and 80 loosely connected at its rear end with an angle lever adapted to rock the skeleton frame, the forward end being pivoted upon a lever adapted for rocking adjustment, and means for laterally rocking the rudder, comprising two flexible connections extended from opposite sides of the rudder forwardly and adapted for independent reciprocal movement.

3. In an airship, a supporting frame, a 90 pair of planes arranged on the frame, and normally in the same horizontal plane, a shaft below each plane, arms extending from each shaft and to which the adjacent plane is secured, each of said shafts having a segment connected therewith, and a common 95 gearing for both segments whereby to operate the same for the purpose set forth.

4. In an airship, a supporting frame, a 100 pair of planes in connection with the frame, and normally in the same horizontal plane, a shaft below each plane, arms on the shaft to which the adjacent plane is connected and means for swinging the shafts in unison.

5. In an airship, a plurality of planes 105 normally lying in the same horizontal plane, and means for simultaneously swinging said planes on an axis below and longitudinally thereof.

6. In an airship, a rudder comprising an 110 arched plane whose concavity is downward, a vertical shaft at the vertical center of the plane on which the plane is journaled, a horizontal shaft at the horizontal center of the plane on which the plane is journaled, and means for swinging said plane on either 115 of said shafts.

7. In an airship, a rudder comprising an arched plane, a vertical shaft at the vertical center of the plane on which the rudder is 120 mounted, and means for swinging said rudder on said shaft.

8. In an airship, a pair of planes arranged alongside each other and normally in the same horizontal plane, means for swinging said planes in unison on an axis arranged below and longitudinally of each of said planes, a pair of side planes below said first named planes, the inner edges of said planes being hinged to the air ship, and means for 125 130

raising and lowering the outer edge of each of said planes.

9. In an airship, a pair of planes normally lying in the same horizontal plane, means for swinging each of said planes on a longitudinal axis, a side plane below each of said first named planes whose inner edge is fixed, yielding means engaging the outer edge of each of said last named planes for normally retaining it in horizontal position, and means for swinging said planes on the fixed edge.

10. In an airship, a pair of planes normally lying in the same horizontal plane, means for swinging each of said planes on a longitudinal axis, a side plane below each of said first named planes whose inner edge is fixed and means for swinging said planes on the fixed edge.

11. In an airship, a pair of planes normally lying in the same horizontal plane, means for simultaneously swinging said planes, a side plane below each of said first

named planes and whose inner edge is fixed, and means engaging the outer edge for 25 swinging the same.

12. In an airship, side planes whose inner edge is fixed, yielding means engaging the outer edge of each of the planes for normally retaining said plane in horizontal 30 position, and means for simultaneously swinging both of said planes on the fixed edge.

13. In an airship, a main frame, a protecting structure within said frame, said structure comprising a series of arched ribs and a cover on the ribs, the arch of the cover projecting at each end for the purpose set forth.

In testimony whereof I have signed my 40 name to this specification in the presence of two subscribing witnesses.

CLIFFORD BEODERICK CRONAN.

Witnesses:

JENNIE WHITNEY CRONAN,
FRANK NATHANIEL MERRILL.
